[57] **CLAIM**

The ornamental design for a toy football, as shown and described.

DESCRIPTION

FIG. 1 is a perspective view of a toy football showing our new design;

FIG. 2 is a side elevational view thereof with the toy football located in an upright teed position;

FIG. 3 is a front elevational view thereof;

FIG. 4 is an elevational view thereof similar to FIG. 2, but with the toy football rotated 90° with respect thereto;

FIG. 5 is an elevational view thereof similar to FIG. 4 but with the toy football rotated 180° with respect thereto; and,

FIG. 6 is a rear elevational view thereof.

The characteristic feature of our design resides in the particular shaped fins in combination with the football as shown.
